United States Patent Office

Des. 183,752
Patented Oct. 21, 1958

183,752

HELICOPTER

Lewis G. Knapp, Stratford, and Leonard G. Sibbick, Bridgeport, Conn., assignors to United Aircraft Corporation, East Hartford, Conn., a corporation of Delaware

Application December 31, 1957, Serial No. 49,083

Term of patent 14 years

(Cl. D71—1)

FIG. 1

FIG. 2

FIG. 3

Fig. 1 is a front elevational view of a helicopter showing our new design;

Fig. 2 is a top plan view thereof with two of the rotor blades broken away for convenience of illustration; and

Fig. 3 is a side elevational view.

The dominant features of the design reside in the portions shown in full lines.

We claim:

The ornamental design for a helicopter, substantially as shown and described.
